INCANDESCENT LAMP

Forrest J. Major, Ocean Park, Calif., assignor of
one-third to Palmer O. Narveson, one-third to
Russel S. Major, both of Los Angeles, Calif.,
and one-third to Elbert S. Major, Atlanta, Ga.

Application August 11, 1936, Serial No. 95,329

17 Claims. (Cl. 176—27)

This invention relates to and has for an object
thereof the provision of a multi-filament incan-
descence lamp having incorporated therewith in
a novel and efficacious manner an improved selec-
tor which is operable while the lamp is mounted
in a socket to selectively connect said filaments
in the lamp circuit.

A particular object of this invention is to pro-
vide in a multi-filament lamp of the character
described, a selector which is simple as to con-
struction, does not increase the bulk of the lamp,
adds but little expense as to cost thereof, and is
subject to a convenient operation to energize any
one of the several filaments without requiring re-
moval or adjustment of the lamp relative to the
socket in which it is mounted.

A further object is to provide a lamp of the
character described having a combined filament
selector and fuse wherein the fuse element serves
as one of the terminals of the lamp circuit and as
a contact element of the selector, and is removable
when "burnt out" whereby to be replaced by an-
other fuse element, without otherwise impairing
the operativeness of the lamp.

An additional object is to provide in a multi-
filament lamp of the character described a fila-
ment selector having an operating member which
is readily accessible for operation when the lamp
is screwed into a socket and which does not ap-
preciable extend outwardly from the lamp so as
to in any manner interfere with shade attach-
ments or the like, said member preferably being
in the form of a flat rotary ring surrounding the
neck of the lamp.

Other objects will appear as the description of
my invention progresses.

I have shown a preferred embodiment of my
improvements in the accompanying drawings,
subject to modification, within the scope of the
 appended claims, without departing from the
spirit of my invention. In said drawings:

Fig. 1 is a top plan view of the lamp of this in-
vention;

Fig. 2 is a sectional view taken on the plane of
line 2—2 of Fig. 1;

Fig. 3 is a sectional view taken on the plane of
line 3—3 of Fig. 2;

Fig. 4 is a perspective view of one of the contact
elements of the selector.

Fig. 5 is an enlarged vertical section of a modi-
fied form of the invention;

Fig. 6 is a sectional view taken on the plane of
line 6—6 of Fig. 5;

Fig. 7 is a fragmentary horizontal section of
another modified form of the invention; and

Fig. 8 is a fragmentary horizontal section of the
form of the invention shown in Fig. 7.

One embodiment of this invention as shown in
detail in the accompanying drawings comprises
the usual lamp bulb 1 having its neck 2 cemented
within a socket sleeve 3, the outer portion of
which has the usual threads 4. Mounted in the
bulb are a plurality of filaments 5 having a com-
mon ground conductor 6 connected at 7 with the
sleeve 3 whereby the latter will serve as one ter-
minal of the lamp circuit.

Each of the filaments has a separate conductor
8 embedded in a non-conducting plug or closure
9 cemented or otherwise held within the sleeve
3, there being tubular members 10 of conducting
material held in said plug and in which the con-
ductors 8 are secured in electrical contact ther-
with.

My improved selector, by means of which any
one of the filaments may be energized as desired
and which also includes a fuse arranged in a par-
ticularly advantageous relation thereto, gener-
ally comprises a contact element 11 removably
and frictionally held in a bore 12 formed cen-
trally through the closure 9, filament contacts 13,
plungers 14 of non-conducting material for mov-
ing said contacts into engagement with the ele-
ment 11, and an operating ring 15 rotatable on
the sleeve 3 to actuate plungers 14.

As here shown, the element 11 includes axially
aligned spaced contact terminals 16 and 17 which
are exposed at the outer and inner ends of the
closure 9, the outer terminal 16 serving as one
terminal of the lamp socket and the inner termi-
nal 17 being arranged to be engaged by the
filament contacts 13. A tubular member 18 of
non-conducting material and which fits snugly
in the bore 12 holds in its end the said terminal
contacts 16 and 17, with the latter connected by
a fuse element 19. The outer terminal 16 has an
enlarged outer end or head 16' which facilitates
gripping and removal or insertion of the entire
element 11. The inner terminal or contact 17 has
a reduced end 17' extending into an enlargement
20 of the bore 12 to provide adequate space for
movement of the contacts 13 into and out of en-
gagement with the end 17'.

As here shown, the contacts 13 have extensions
21 affixed to and electrically contacted with the
members 10 for the conductors 8, said extensions
lying against the inner end of the closure 9 with
the contacts 13 extended into the enlargement 20
of the bore 12 and normally spaced from the end
16'.

The plungers 14 are radially slidably mounted 55

in the closure 9 and extend outwardly therefrom through aperture 22 in the sleeve 3, being normally thus extended by the spring action of the contacts 13 which are engaged with the inner end 5 of said plungers. The projecting outer ends of these plungers engage in a circumferential groove 23 formed in the inner side of the selector ring 15 and thereby rotatably support the ring upon the inner unthreaded portion of the sleeve 3. 10 One wall of this groove is formed with a cam surface 23 for engagement with the plungers 14. A shoulder 24 in said groove limits the movement of the ring to rotation in one direction. Thus, when the lamp is being screwed into a socket the 15 ring will not be turned should it frictionally engage said socket.

It will now be seen that to connect a filament in the lamp circuit it is only necessary to rotate the ring until the cam 23 engages the selected 20 plunger 14 and pushes the latter inwardly. Upon being pushed inwardly this plunger will engage and move the contact 13 opposite thereto into engagement with the end 17' of the element 11, and the lamp circuit will be established for one of 25 said filaments.

In the modified form of the invention as shown in Figs. 5 and 6, the metal sleeve or base 30 is equipped with the usual closure 31 and has the contact fuse element 32 of the same construction 30 as the one 11 in the other form of the invention.

The filaments not shown have a common ground conductor 33 connected with the sleeve 30 and conductors 34 connected with and forming a part 35 of contact means carried by the closure. A ring 36 is rotatable on the sleeve 30 in the same manner as the ring 15 and has a groove 37.

As here shown the contact means comprise helical springs 38 which are mounted in radial bores 39 in the closure 31 and have their outer ends engaged with laterally extended contact terminals 40 of the conductors 34. These terminals 40 are extended through insulating sleeves 41 into the groove 37 of the ring 36, and are adapted to engage a contact segment 42 which is counter sunk in said groove. This segment is of such extent that it may be engaged with but one of the terminals 40 or with two or all of said terminals at the same time, whereby one, two or all of the 50 filaments may be energized as desired.

The contact segment 42 is electrically connected in the lamp circuit by means of a helical spring 43 having its inner end engaged with the contact member 32 and its outer end engaged with the 55 said contact segment, there being an insulating sleeve 44 corresponding to the sleeves 41.

A plunger 45 of insulation material is slidably supported in the lamp base or sleeve 30 and in a socket 46 in the closure 31. This plunger is extended by a spring 47 so as to slidably engage in the groove 37 and thereby assist in holding the ring 36 for free rotation on the lamp. It will now be seen that in this form of the invention the ring 36 may be rotated to selectively connect the several filaments in the lamp circuit and to simultaneously connect two or all of said filaments.

In the modification shown in Figs. 7 and 8, the construction and arrangement is the same as in the other form of the invention except that the 70 helical spring contact members 48 (see Fig. 7) are soldered or otherwise connected, as at 49, with the filament conductors 50 and are extended through the metal base 51 into the groove 52 of the rotatable ring 53, there being an insulation sleeve 54 for each spring. The contact segment

55 in the ring 53 is connected in the lamp circuit by a helical spring contact 56, one end of which engages the lamp terminal contact element 57 and the other end engages the said segment. An insulation tube 58 insulates the spring contact 56 from the metal base sleeve 51. In this form, as in the form shown in Figs. 5 and 6, when the ring is turned the contact segment will be caused to engage the contact spring 56 for one of the filaments or to simultaneously engage two or all 10 of the contacts whereby one, two or all of the filaments may be energized.

What I claim is:

1. An incandescent lamp comprising a bulb, a plurality of filaments therein, a sleeve of conducting material secured to said bulb, a closure of non-conducting material within said sleeve, a conductor connecting all of said filaments with said sleeve, a conducting element mounted in said closure and having its outer end exposed at the outer end of said closure to serve as a terminal of the lamp circuit, a plurality of contacts, conductors connecting said contacts with said filaments, and means for selectively electrically connecting said contacts with said conducting element 25 including an actuator operable exteriorly of said sleeve, while the lamp is mounted in a socket, and members associated with said contacts and extending laterally outward through said sleeve and being engaged with said actuator. 30

2. An incandescent lamp comprising a bulb, a plurality of filaments therein, a sleeve of conducting material secured to said bulb, a closure of non-conducting material within said sleeve, a conductor connecting all of said filaments with 35 said sleeve, a conducting element mounted in said closure and having its outer end exposed at the outer end of said closure to serve as a terminal of the lamp circuit, a plurality of contacts, conductors connecting said contacts with said filaments, means for selectively electrically connecting said contacts with said conducting element including a rotary actuator operable exteriorly of said sleeve, while the lamp is mounted in a socket, and members slidably supported by said sleeve 40 and engaging said contacts, and supporting said actuator on said sleeve. 45

3. An incandescent lamp comprising a bulb, a plurality of filaments therein, a sleeve of conducting material secured to said bulb, a closure of non-conducting material within said sleeve, a conductor connecting all of said filaments with said sleeve, a conducting element mounted in said closure and having its outer end exposed at the outer end of said closure to serve as a terminal of the lamp circuit, and its inner end exposed adjacent to the inner end of said closure, a plurality of contacts carried by said closure and adapted to be selectively engaged with said inner end of said conducting element, conductors connecting said contacts with said filaments, means for selectively moving said contacts into engagement with said conducting element including an actuator operable exteriorly of said sleeve, while the lamp is mounted in a socket, and plungers 55 interposed between and engaging said actuator and contacts, said actuator being in the form of a ring and having a groove therein in which said plungers are engaged. 60

4. An incandescent lamp comprising a bulb, a plurality of filaments therein, a sleeve of conducting material secured to said bulb, a closure of non-conducting material within said sleeve, a conductor connecting all of said filaments with 70 said sleeve, a conducting element mounted in said sleeve, 75

closure and having its outer end exposed at the outer end of said closure to serve as a terminal of the lamp circuit, and its inner end exposed adjacent to the inner end of said closure, a plurality of contacts carried by said closure and adapted to be selectively engaged with said inner end of said conducting element, conductors connecting said contacts with said filaments, means for selectively moving said contacts into engagement with said conducting element including an actuator operable exteriorly of said sleeve, while the lamp is mounted in a socket, plungers interposed between and engaging said actuator and contacts, said actuator being in the form of a ring and having a groove therein in which said plungers are engaged, and a cam surface in said groove arranged to engage said plungers.

5. An incandescent lamp comprising a bulb, a plurality of filaments therein, a sleeve of conducting material secured to said bulb, a closure of non-conducting material within said sleeve, a conductor connecting all of said filaments with said sleeve, a conducting element mounted in said closure and having its outer end exposed at the outer end of said closure to serve as a terminal of the lamp circuit, and its inner end exposed adjacent to the inner end of said closure, a plurality of contacts carried by said closure and adapted to be selectively engaged with said inner end of said conducting element, conductors connecting said contacts with said filaments, and means for selectively moving said contacts into engagement with said conducting element including an actuator operable exteriorly of said sleeve, while the lamp is mounted in a socket, said conducting element having said ends thereof spaced apart and a fuse element joining said ends.

6. In an incandescent lamp, a bulb, a sleeve of conducting material fixed to said bulb and having a threaded portion, a closure of non-conducting material in said sleeve, a plurality of filaments in said bulb, a plurality of contact members, conductors connecting filaments with said sleeve and with said contacts, a conducting means in said closure having its outer end exposed at the outer end of said closure and its inner end exposed for engagement with at least one of said contacts, and means operable on the exterior of said sleeve between the threaded portion and the inner end of the sleeve for selectively engaging said contacts and connecting said filaments in the lamp circuit, said last named means including a ring rotatably mounted on the exterior of said sleeve, and members associated with said contacts and slidably supported by said sleeve and extensible therethrough for supporting said ring.

7. In an incandescent lamp, a bulb, filaments therein, a sleeve of conducting material fixed to said bulb, a body of non-conducting material closing said sleeve, a lamp terminal contact on said body, and means for selectively connecting said filaments with said sleeve and contact including a ring rotatable on said sleeve, and members slidably supported by and extending laterally outwardly from said sleeve and being movable by rotation of said ring for effecting electrical connection between said filaments and said sleeve.

8. In an incandescent lamp, a bulb, filaments therein, a sleeve of conducting material fixed to said bulb, a body of non-conducting material closing said sleeve, a lamp terminal contact on said body, means for selectively connecting said filaments with said sleeve and contact including a ring rotatable on said sleeve, and having a circumferential groove on the inner periphery

thereof, plungers slidably supported by said body and sleeve and having their outer terminals engaged in said groove, a cam surface in said groove, and spring contacts engaging the inner ends of said plungers.

9. In an incandescent lamp, a bulb, filaments therein, a sleeve of conducting material fixed to said bulb, a body of non-conducting material closing said sleeve and having a bore therein provided with an enlarged inner end, a conducting element in said bore and having an outer terminal exposed at the outer end of said body and an inner terminal exposed in said enlargement of said bore, a plurality of spring contacts fixed to said body and being movable to engage said inner terminal, conductors for connecting said filaments with said sleeve and said contacts, a ring rotatable on said sleeve and having a groove therein formed with a cam surface, and a plurality of plungers slidably supported by said body and sleeve and having their inner ends engaged with said spring contacts and their outer ends engaged in said groove.

10. In an incandescent lamp, a bulb, filaments therein, a sleeve of conducting material fixed to said bulb, a body of non-conducting material closing said sleeve and having a bore therein provided with an enlarged inner end, a conducting element in said bore and having an outer terminal exposed at the outer end of said body and an inner terminal exposed in said enlargement of said bore, a plurality of spring contacts fixed to said body and being movable to engage said inner terminal, conductors for connecting said filaments with said sleeve and said contacts, a ring rotatable on said sleeve and having a groove therein formed with a cam surface, and a plurality of plungers slidably supported by said body and sleeve and having their inner ends engaged with said spring contacts and their outer ends engaged in said groove, said terminals of said conducting element being spaced apart and a fuse element joining said terminals.

11. In an incandescent lamp a bulb, filaments therein, a sleeve of conducting material fixed to said bulb, a body of non-conducting material closing said sleeve, a lamp terminal contact element on said body and means for selectively connecting said filaments with said sleeve and lamp terminal contact element, including a ring of insulation material rotatable on said sleeve, and circuit closing members actuated by rotation of said sleeve, said sleeve having a circumferential groove and laterally slidably members associated with said circuit closing members and being engaged in said groove, said sleeves having openings therein through which said slidably members are extensible.

12. In an incandescent lamp, a bulb, filaments therein, a sleeve of conducting material fixed to said bulb, a lamp terminal contact insulated from said sleeve, means for selectively connecting said filaments with said sleeve and contact including a ring rotatable on said sleeve, said ring having a groove circumferentially thereof, a contact segment in said groove, said sleeve having openings therein, filament contact portions extended through said openings into said groove for engagement with said contact segment, and insulation sleeves mounted in said openings and through which said contact portions extend.

13. In an incandescent lamp, a bulb, filaments therein, a sleeve of conducting material fixed to said bulb, a lamp terminal contact insulated from said sleeve, means for selectively connecting said

filaments with said sleeve and contact including a ring rotatable on said sleeve, said ring having a groove circumferentially thereof, a contact segment in said groove, said sleeve having openings 5 therein, contact elements connected with said filaments and extended through said openings into said groove for engagement with said contact segment and for retaining said ring on said sleeve, one of said contact elements being engaged with 10 said lamp terminal contact and said segment at all times.

14. In an incandescent lamp, a bulb, filaments therein, a sleeve of conducting material fixed to said bulb, a body of non-conducting material 15 closing said sleeve, a lamp terminal contact on said body, means for selectively connecting said filaments with said sleeve and contact including a ring rotatable on said sleeve, said ring having a groove circumferentially thereof, a contact segment 20 in said groove, said body having radial bores therein, helical springs mounted in said bores, said sleeve having openings, contact portions extended by said springs through said openings into said groove for engagement with said contact 25 segment, and insulation sleeves mounted in said openings and through which said contact portions extend, one of said springs being engaged with said lamp terminal contact and segment at all times, said segment being countersunk in said 30 groove and adapted to be simultaneously engaged with all said contact portions.

15. In an incandescent lamp, a bulb, filaments therein, a sleeve of conducting material fixed to said bulb, a body of non-conducting material 35 closing said sleeve, a lamp terminal contact on said body, and means for selectively connecting said filaments with said sleeve and contact including a ring rotatable on said sleeve, said ring having a circumferential groove therein, a contact segment in said groove, a plurality of socket 40 openings in said body, helical spring contacts in said socket openings, conductors leading from said filaments to and being engaged with said spring contacts, said sleeve having openings 45 therein registering with said groove, contact portions extending through said sleeve openings into

said sleeve under the tension of and being in contact with said springs, tubular members of insulation material engaged in said sleeve openings and said groove and through which said portions extend, one of said spring contacts having its 5 terminals engaged at all times with said lamp terminal contact and said contact segment.

16. In an incandescent lamp, a bulb, filaments therein, a sleeve of conducting material fixed to said bulb, a body of non-conducting material 10 closing said sleeve, a lamp terminal contact on said body, and means for selectively connecting said filaments with said sleeve and contact including a ring rotatable on said sleeve, said ring having a circumferential groove therein, a contact segment 15 in said groove, a plurality of socket openings in said body, helical spring contacts in said socket openings, conductors leading from said filaments to and being engaged with said spring contacts, said sleeve having openings 20 therein registering with said groove, contact portions extending through said sleeve openings into said sleeve under the tension of and being in contact with said springs, tubular members of insulation material engaged in said sleeve openings 25 and said groove and through which said portions extend, one of said spring contacts having its terminals engaged at all times with said lamp terminal contact and said contact segment, said 30 portions comprising terminals of said conductors.

17. An incandescent lamp comprising a base including terminal contacts, a bulb carried by said base, filaments in said bulb and switch means on the base for connecting said filaments with said terminal contacts and including a rotary 35 actuator, and switch members extending outwardly from the base and yieldably engaging, inwardly movable relative to and rotatably supporting said rotary actuator, said rotary actuator having a groove therein in which said switch 40 members are engageable, said rotary actuator being insertible into position on and removable from the base upon inward movement of said switch members.

FORREST J. MAJOR. 45
